(57) **CLAIM**

The ornamental design for a water skimmer, as shown and described.

DESCRIPTION

FIG. 1 A front elevation view of a water skimmer showing my new design with the water skimmer weir shown in its closed position;

FIG. 2 A front elevation view thereof;

FIG. 3 A rear elevation view thereof;

FIG. 4 A right side elevation view thereof;

FIG. 5 A top plan view thereof;

FIG. 6 A left side elevation view thereof; and,

FIG. 7 The same as FIG. 1, with the weir in its open position. The bottom plan view is flat, unornamented and contains no claimed features; therefore, it is not illustrated.
